DOUBLE JAW WRENCH

Homer A. Mead, Turlock, Calif., assignor to Mas-
terench Corporation, Turlock, Calif., a corpo-
ration

Application January 16, 1935, Serial No. 2,019

1 Claim. (Cl. 81—98)

This invention relates to wrenches of the swing-
ing jaw type such as are shown in my Patents
Nos. 1,735,257 and 1,885,616, and particularly repre-
sents improvements over the structure of the
latter patent.

My main object is to provide a wrench of this
character having separate work engaging faces
in the swinging jaw which are spaced different
distances from the pivot of the jaw so as to take
10 nuts, etc., of many different sizes, and a single
curved work engaging face on the fixed jaw; the
different faces of the two jaws being arranged
relative to each other so that regardless of the
position of the swinging jaw and its face relative
15 to the fixed jaw and its face, and nut etc., large
or small will be squarely engaged between the
corresponding opposed faces, or so that one face
of a nut will rest flatly against the face of the
swinging jaw while the opposed face of the nut
20 is centrally tangent to the curved face of the
fixed jaw. By means of this structure not only
may the wrench be used for a great number of
different sized nuts, etc. (without any excessive
size or arc of swing of the movable jaw being
25 necessary) but all such nuts will be properly held
against any tendency to slip from holding rela-
tion with the jaws.

A further object of the invention is to produce
a simple and inexpensive device and yet one which
30 will be exceedingly effective for the purpose for
which it is designed.

These objects I accomplish by means of such
structure and relative arrangement of parts as
35 will fully appear by a perusal of the following
specification and claim.

In the drawing similar characters of reference
indicate corresponding parts in the several views:

Figure 1 is a side elevation of my improved
40 wrench showing the swinging jaw in different
positions when engaged with relatively large nuts
of different sizes.

Figure 2 is a similar view showing the swinging
jaw in various positions when engaged with rela-
45 tively small nuts of varying sizes.

Referring now more particularly to the char-
acters of reference on the drawing, the wrench
comprises a handle and shank portion 1 having
on one end a curved fixed jaw 2 provided along
50 one side with a curved row of ratchet teeth 3,
facing toward the upper end of the jaw. Although
in the main this curved row follows an arc struck
from a center C, the initial portion of the curve
at the upper end of the jaw is of greater radius
55 than the remainder; the centers of the two axes

of curvature however lying in a common radial
line.

Pivoted at P on the neck 4 of the shank just
below the fixed jaw is the swinging jaw 5. This
is normally held in a relatively closed position by
5 a spring 6 which in the present case is shown as
being arranged as in my Patent No. 1,735,257
above mentioned. Formed on the swinging jaw
toward its outer end and on the side facing the
fixed jaw is a flat work engaging ratchet toothed
10 face 7; while another similar face 8 is also formed
on the swinging jaw intermediate the face 7 and
the pivot P. The face 8 however is positioned so
as to be always closer to the curved face 3 of the
fixed jaw than is the face 7, and is disposed in
15 a plane at an obtuse angle to that of the face 7
in such a manner that the planes of the faces 7
and 8 intersect each other practically at the inner
end of face 7.

With any position of the swinging jaw there-
fore smaller nuts may be held between the faces
20 8 and 3 than between the faces 7 and 3. The faces
7 and 8 are set so as to be substantially tangent
in all positions to circles of different sizes pro-
jected from the point C as a center.

From the above description therefore it will be
seen that a series of small nuts or like parts of
30 different sizes may be efficiently held between
the faces 8 and 3 with any setting of the swinging
jaw and without any tendency of the nuts to slip
from place. Likewise a series of relatively large
nuts of different sizes may be efficiently held be-
35 tween the faces 7 and 3 with any setting of the
swinging jaw and without any tendency of such
nuts to slip. This is because, as indicated on the
drawing, with any such position of the swinging
jaw, a nut is not only freely engaged on one side
40 by the corresponding face of the swinging jaw,
but on its opposite side is centrally engaged by
the teeth 3 of the fixed jaw.

From the foregoing description it will be readily
seen that I have produced such a device as sub-
stantially fulfills the objects of the invention as
set forth herein.

While this specification sets forth in detail the
present and preferred construction of the device,
still in practice such deviations from such detail
may be resorted to as do not form a departure
from the spirit of the invention, as defined by
the appended claim.

Having thus described my invention, what I
claim as new and useful and desire to secure by
Letters Patent is:

A wrench comprising a shank having a curved
gripping surface on one end, said surface being

formed of a pair of arcs of different radii whose centers lie on a common radial line, a swinging jaw pivoted on the shank and separate spaced gripping faces on said movable jaw to cooperate with the gripping surface, the planes of said faces being disposed at an obtuse angle to each other and at different distances from the gripping surface; the centers of curvature of said surface be-

ing so located that with the swinging of the movable jaw to any position, both said faces will be substantially tangent at points intermediate their ends to circles projected from the center of curvature of the corresponding portion of said gripping surface. 5
